UNITED STATES PATENT OFFICE.

JOHN BENDER, OF DEUNQUAT, OHIO.

RAILROAD-RAIL JOINT.

SPECIFICATION forming part of Letters Patent No. 309,123 dated December 9, 1884.

Application filed May 23, 1884. (No model.)

To all whom it may concern:

Be it known that I, JOHN BENDER, a citizen of the United States, residing at Deunquat, in the county of Wyandot and State of Ohio, 5 have invented certain new and useful Improvements in Railroad-Rail Joints; and I do declare the following to be a full, clear, and exact description of the invention, such as will enable others skilled in the art to which it appertains 10 to make and use the same, reference being had to the accompanying drawings, and to letters or figures of reference marked thereon, which form a part of this specification.

Figure 1 of the drawings is a transverse sectional view of my device, taken on the line x' x' of Fig. 2. Fig. 2 is a side view of the same. Fig. 3 is a bottom view. Fig. 4 is a perspective view, and Figs. 5, 6, and 7 are perspective detail views.

20 The object of this invention is to provide a coupling or fastening whereby the ends of railway-rails may be secured in relative position without fastening them by means of bolts.

The invention consists in the construction 25 and novel arrangement of parts, as hereinafter set forth, and pointed out in the appended claim.

In the accompanying drawings, the letter A designates the ends of the rails. At each end 30 the rail is cut away on top through the head, so that the web and foot project, as shown at B.

C represents the end of the head, and D the shoulder of the web. When the ties to which 35 the coupling is to be secured are of soft timber, the said ends are rabbeted underneath, as indicated at F.

G represents the cap, having a head portion, H, and side walls, K, which extend downward 40 therefrom on each side of an interval, L, of sufficient size to receive the rabbeted ends B of the rails and allow a little play endwise.

The lower ends of the side walls are turned outward to form feet, as indicated at m, which are provided with apertures a for the passage 45 of the spikes, whereby the cap-piece is to be secured to the tie. Sometimes a transverse stay is formed between the side walls of the cap-piece. In the feet of the cap-piece are made the rectangular notches or seats b, to receive 50 the ends of the base-plate z, which extends transversely under the rail ends, the edges of said plate fitting into the rabbets F of said ends. The outer ends of this transverse plate project through the notches b, and 55 are provided with upwardly-turned flanges c, which engage the sides of the cap-piece. When this plate is used, it is not necessary to form a transverse stay in the cap-piece.

When oak ties are used, the cap-piece may 60 be made without the notches, and the lower plate may be made larger than the cap-piece, and may have side notches and flange projections, whereby it engages or is locked to the feet of the cap-piece.

Having described this invention, what I claim, and desire to secure by Letters Patent, is—

The combination of the end-rabbeted rails having the web shoulders, as shown, and the 70 under rabbets, the headed cap-piece having side walls and its feet provided with the vertical notches and perforations, and the transverse base-plate having end flanges to engage the notches in the feet of the said cap-piece, 75 whereby the whole may be secured together without the use of bolts, substantially as shown and described.

In testimony whereof I affix my signature in presence of two witnesses.

JOHN BENDER.

Vitnesse:

W. C. HARPER,
WILBER BROWN.
